UNITED STATES PATENT OFFICE.

EDWARD E. CLEMENT, OF WASHINGTON, DISTRICT OF COLUMBIA.

TELEPHONIC APPARATUS.

1,109,621.

Specification of Letters Patent. Patented Sept. 1, 1914.

Application filed November 13, 1907, Serial No. 402,027. Renewed July 3, 1914. Serial No. 848,995.

To all whom it may concern:

Be it known that I, EDWARD E. CLEMENT, a citizen of the United States, residing at Washington, in the District of Columbia, have invented certain new and useful Improvements in Telephonic Apparatus, of which the following is a specification, reference being had therein to the accompanying drawing.

10 My invention relates to telephonic apparatus and especially to automatic switches used for interconnecting lines and for similar purposes.

15 The object of the invention is to simplify the design and construction of such switches, at the same time rendering them more efficient in operation.

A switch of the type to which this invention relates usually has a plurality of 20 fixed or "bank" contacts, one or more movable contacts, and one or more electromagnets for moving the same, together with a release or restoring magnet for returning the parts to normal condition when the 25 switch is in a condition of disuse. In order to set the movable contacts with accuracy, a spindle has been provided, carrying one or more ratchets, worked by pawls actuated by the working electromagnets, together with a 30 stop pawl or detent controlled by the release magnet. These parts have all been assembled on a frame, usually of cast metal, with sundry adjustments made necessary by the fact that the individual parts were not directly joined but depended upon the frame 35 for their interconnection.

In the present switch, I provide a frame of the simplest and most elementary character, in which the spindle is held so that 40 it can both reciprocate and rotate. The frame is connected to the bank contacts so as to be readily detachable therefrom, carrying with it all the working parts. The movable contacts or wipers are attached to the 45 spindle, which also carries what I shall call a "vertical" ratchet for producing reciprocating motion, and a "rotary" ratchet for turning it. A pivoted stop pawl or detent is attached to the frame with a single pro- 50 jection or toe of peculiar shape adapted to engage and act upon both the rotary and the vertical ratchets. Three magnets are mounted upon the frame, each forming a complete unit, with all its operating parts 55 directly connected together, assembled and adjusted upon the magnet before being at-

tached to the frame. When in position, each magnet is attached to the frame at one end only, and the working parts are actuated by means of bell crank levers pivoted on knife edges at the outer extremities of the magnets. From its peculiarity of construction, which gives a very positive action, due to the long lever arms and small air gaps, similar to that of the best types of relays used in telephonic work, I may call my invention a bell crank or "relay type" switch.

60 My invention is illustrated in the accompanying drawings in which—

Figure 1 is a side view of a switch embodying my invention, and having a positive release action. Fig. 2 is a top plan view of the same. Fig. 3 is a rear elevation thereof. Fig. 4 is a side elevation of a switch having a two-motion or negative release. Fig. 5 is a top plan view of the same. Fig. 6 is a rear elevation thereof, and Fig. 7 is a detail of the release mechanism on the inside of the frame, looking in the direction of the arrow in Fig. 4. Fig. 8 is a detail view showing adjustments.

70 Referring to the drawings, and especially to Figs. 1, 2 and 3, I have therein shown the bank contacts at 1 and 2. These are supported upon transverse angle pieces 75 3 and 4, by means of which they are attached to the so-called "mounting" strips, which are iron bars horizontally secured across the bays in suitable racks or frames. This method of mounting, forming no part of 80 the present invention, I have not deemed it necessary to show any part of the racks or frames, but it will be understood that the vertical faces of the angles 3 and 4 are screwed against upper and lower mounting 85 strips, so as to support the switch as a whole with the axis of its spindle vertical. The frame 5, formed in a shallow U-shape, is secured at its upper and lower ends to the angle pieces 3 and 4, so as to be detachable 90 therefrom. I have shown the securing means as screws 6 and 7, but obviously these may be varied at will. A spacing or guide strip 8 is secured within the frame, parallel with the long side 5^a thereof. The spindle 95 9 is mounted vertically, with its ends journaled in the upper and lower limbs of the frame, so that it may both reciprocate and turn therein. Upon the spindle are secured a vertical ratchet 10 and a rotary ratchet 100 11. The vertical ratchet consists of a series of circular teeth formed on a sleeve secured 105

upon the spindle. The rotary ratchet has a flat wheel secured concentric with and at the top of the vertical ratchet. The stop pawl 12 engages this rotary ratchet at a point 13, which is spaced a sufficient number of teeth away from the point of engagement of the rotary pawl to avoid interference therewith. The stop pawl 12 is provided with ears by means of which it is pivoted at top and bottom upon the guide strip 8. It has a projecting toe 15, which has two faces, one 15^a shaped to engage the rotary ratchet, and the other 15^b shaped to engage the vertical ratchet. Thus the single dog 15 serves as a detent for both ratchets. Of course, as the spindle rises the rotary ratchet 11 becomes disengaged from the edge 15^a of the stop pawl, but before it does so it passes into engagement with a knife edge 16 fixed on the inner face of the guide strip 8. The spindle is supposed to be turned the desired number of steps before it is elevated, and so the function of the stop pawl is performed with respect to the rotary ratchet before the spindle rises. As it rises the knife edge 16 prevents any further rotation either backward or forward.

A metal cup 17 is secured around the lower end of the spindle, and within this a coil spring is provided which has a constant tendency to turn the spindle back to its zero position, the cup carrying a stop bearing against the guide strip 8, and one end of the spring being attached to the cup on the inside, while its other end is attached to the spindle.

The vertical motion of the spindle and the wipers is produced by means of the magnet 18, which has a core 19, heads 20 and 21, an iron return bar 22, a bell crank armature 23, balanced on the knife edge 24, and normally held with its long arm 25 flat against the top of the return bar by means of a long spiral spring 26, at one end attached to a U-shape anchor 27 set up in the angle of the return bar 22, and at the other end adjustably connected to a spring post 28 secured upon the armature near the knife edge. The armature is held against displacement by a screw 29 passing through its transverse member into the end of the return bar. At its free end, the arm 25 is bent at 30 and slotted to receive the vertical pawl 31, pivoted at 32 and provided with a suitable spring to impel its point forward when the arm 25 is lifted. The frame piece 5^a is slotted at 320 to pass the arm 25, and to permit the withdrawal of the pawl when the magnet is detached from the frame.

60 The rotary magnet 33 is provided with precisely the same parts as the vertical magnet 18, that is to say it has a core, heads, return bar, knife edge, bell crank armature, long projecting arm carrying a pawl at its end, and retractile spring similar to that of

the vertical magnet. The release magnet 34 is in every respect similar, with the same parts thus recapitulated. In other words, in the type of switch shown in Figs. 1, 2 and 3, the magnets 18, 33 and 34 are substantially the same, and all their parts are interchangeable excepting the lever ends and the pawls. The rotary pawl 35, its attachment to the lever 36 of its magnet, and its propelling spring 37 are best shown in Fig. 2. 70 This pawl 35 works in a slot 38 cut in the guide strip 8. The vertical pawl 31 works in a slot 39; and the dimensions of these two slots are such as to regulate and limit the movement of the pawls over their edges. 80

The end of the long lever 40 of the release magnet 34 is perforated to receive a rod or pitman 41, provided with an adjusting nut 42 and connected at its other end with a tail piece 43 on the stop pawl or detent 12. When the armature 44 is attracted therefore, the lever arm 40 is thrown out from the return bar, the tail piece 43 is pulled over, and the toe 15 is removed from engagement with either the vertical or rotary ratchet, so as to permit gravity to bring down the spindle and its parts to the position shown in Fig. 1, and thereafter to permit the spring in the cup 17 to turn the spindle back to zero position. 90

The switch shown in Figs. 1, 2 and 3, and covered by the foregoing description, is what is known as a single-motion or positive-release switch, that is to say, its parts are released and returned to normal upon the energization of the magnet 34. In some portions of an automatic circuit it is necessary to employ switches which will not release on the positive impulse or energization of the magnet 34, but will release only upon the deenergization of said magnet after it has been effectively energized. Such switches are called two-motion or negative-release switches. Such a one is shown in Figs. 4 to 7 inclusive. It is unnecessary to describe the working parts and magnets shown in these figures, as they are precisely the same as the corresponding parts in Figs. 1, 2 and 3. The only differences are found in the release mechanism. This is composed of three principal parts, viz., the armature lever 40, the stop pawl 12, and a dummy pawl or false trip 50. The trip 50 is pivoted on the opposite side of the guide strip 8 in precisely the same manner as the detent 12 on its side. At its upper end the strip carries an ear 51 which is connected through a pitman 52 to the end of the armature 40. At its lower end the strip 50 carries a projection 53 bent at right angles, and upon this is secured a transverse spring 54 having an eye or opening 55 normally lying just inside of a projection 56 near the lower end of the detent 12. This detent 12, and the trip 50 are each provided with a spiral spring nor- 110 115 120 125 130

mallly tending to turn them on their pivots so as to throw the forward edges toward the rotary ratchet wheel and the rear edges apart. The retractile spring of the trip 50 is made much stronger than that of the detent 12, and the flat spring 54 is given a considerable pressure or set, against the end of the tooth or projection 56.

The operation of this device is as follows:

- 10 When the release magnet is energized, the arm 40 is thrown out, and the trip 50 is turned on its pivot so as to slide the spring 54 along until its eye 55 slips over the tooth 56 of the detent 12, the normal set of the 15 spring causing it to make its engagement as soon as the eye comes over the tooth. Upon the subsequent deenergization of the magnet 34, the arm 40 is drawn down by its spring against the return bar, the trip is turned by 20 its spring so far as the length of the pitman 52 will permit, and since its flat spring 54 is in engagement with the rearwardly extended tooth 56 of the detent 12, it turns the latter on its pivot, and disengages its toe 25 from the rotary and vertical ratchets, holding it in its disengaged position until the switch again comes into use.

In order to release the detent 12 and permit it again to engage the ratchets, I provide a pin or stud 57 set vertically in the arm 58 of the rotary magnet 33. As already stated the rotary magnet is energized before the vertical, and at the first movement of the rotary armature, the pin 57 strikes a bent 30 end portion 54^a forming a cam on the end of the spring 54 so as to force said spring back toward the magnets and withdraw it thereby from engagement with the tooth 56 of the detent 12. The spring on the detent then 35 turns it so that its toe will engage the ratchets.

The electrical connections of my switch are not shown since they form no part of the present invention. Assuming that subscribers' lines or trunk lines or operators' circuits, as the case may be, are connected to the bank contacts, the wipers 60 may be caused to engage any particular pair of contacts and thereby connect the corresponding 40 line or trunk or operator with the switch circuit and whatever it is connected with, in the following manner: The bank contacts being arranged in vertical rows, with preferably ten pairs in each row, in order to 45 select an individual pair, the rotary magnet 33 is first energized by sending through it a number of electrical impulses corresponding to the number of the row in which the desired pair of contacts is to be found. 50 These will cause the rotary magnet to attract its armature and move the pawl 35 a corresponding number of times, each movement stepping the spindle around on its axis a space corresponding to one tooth on 55 the ratchet wheel. The wipers are thus

brought beneath and in line with the desired row of contacts. A suitable number of electrical impulses is then sent through the vertical magnet 18, which attracts its armature a corresponding number of times and steps the spindle up the same number of steps, whereby the wipers are caused to rest upon the desired pair of contacts in the row. The spindle is held in this position, with all the magnets energized, until the usefulness 70 of the connection is at an end, whereupon electrical current is caused to energize the magnet 34, which attracts its armature and releases the switch in either one of the two ways heretofore described.

I am aware that a number of changes may be made in the details of this design without departing from the characteristic features thereof. These are the end mounting of the operating magnets, by which I avoid the use 75 of a complicated frame, and make each magnet detachable; the provision of a guide strip 8 which leaves a vacant space between itself and the member 5^a on the frame in which the working parts can be moved; the provision of a false or dummy trip for making a two-motion release; and the specific structure and arrangement of the working magnets. It will be observed that I have provided the bell crank armatures with 80 spiral retractile springs. The means by which I do this constitute a point of novelty and I shall claim the same. These springs are well known to be superior to flat or leaf springs, but their use has heretofore been 85 unknown and presumably impossible with this type of armature. The use of knife edges and an end support for the armature levers, whereby adjustments may be avoided, also constitute a point of novelty which 90 I shall claim. Among the changes which can be made are the positive connection of the armature 40 and the false trip 50, so that the armature in its movement will positively move the trip 50 in both directions.

The method of attaching the ratchets, the cup 17, and the wipers to the spindle may be varied, since these parts may be attached separately and directly to the spindle, in the ordinary manner. I prefer, however, to 100 mount them altogether upon a separate sleeve or tube which can have the ratchet teeth cut in it and the other parts attached to it. The spindle then becomes a plain steel rod, to which the sleeve is attached by simple 105 positive means such as the set screw shown in the drawings. By this construction, if it is desired to remove the wipers or ratchets for any reason, it is only necessary to loosen the set screw, slip out the spindle endwise, 110 and remove the tube with all the parts on it from the side of the frame. I believe this to be a very important departure.

A very important point which I wish 115 clearly understood is that I am not limited 120

in my design to the use of single spool magnets, but can change these to double spool, by using a yoke at the rear end and broadening the armature so it will extend across the front end of the cores. Such an arrangement of a relay, with a similar armature is shown for example in my prior applications No. 293,149, filed December 23, 1905 and No. 331,564, filed August 22, 1906. The particular magnet which sometimes requires to be made double because of its heavy work and the necessity for quick sharp action, is the vertical. I have found it advantageous, however, to make the rotary magnet also double, in which case the frame of the switch is correspondingly lengthened and the number of teeth in the vertical ratchet may be increased to allow for the greater height of the rotary magnet on the frame. The release magnet may also be made double poled, if required, but this is hardly ever necessary. In order to decrease the cost of assembling the switch, adjustments may be added if desired. The engagement of each armature with its knife edge is of course positive, but the air gap and the throw of the lever may be regulated by tapping a screw through the inner end of each armature lever, and putting a lock-nut on the screw, the point of the latter being turned downwardly so that instead of the armature lever resting flat along the top of the return bar, the point of the screw will rest thereon, and by adjusting this up or down, the exact position of the lever and therefore of its connected parts, may be determined. Such an arrangement is shown in Fig. 8. Other adjustments will suggest themselves to those skilled in the art, and it will of course be understood that the addition of any such to the present design is within my present contemplation. Such adjustments are shown in Fig. 8.

All such changes and modifications as do not depart from the spirit of my invention are to be considered as within the scope of the following claims.

I do not claim herein the fixed knife edge, the same having been disclosed and specifically claimed heretofore in my own Patent No. 1,076,020, granted October 21, 1913.

Having thus described my invention what I claim and desire to secure by Letters Patent is—

1. A selective switch for electrical systems comprising a bank of fixed contacts, supporting means therefor, a frame secured thereto, a selective contact adapted to reciprocate within the frame, and self-contained electromagnetic actuating means for said contact mounted upon the outside of the frame and having its actuating parts extending within the frame into operative relation with the said contact.

2. A selective switch for electrical systems comprising a bank of fixed contacts,

supporting means therefor, a frame secured thereto and bridging over the bank, a spindle carrying a selective contact and mounted so as to have motion within the frame, and an actuating mechanism for said spindle so as to have a core secured at one end to the outside of the frame so as to be substantially perpendicular to the axis of the spindle, and working parts extending within the frame into operative relation with the spindle. 75

3. A selective switch for electrical systems comprising bank contacts, supporting means therefor, a frame secured thereto, bridging the bank and spaced away therefrom, a spindle carrying a selective contact 80 and mounted so as to have motion within said frame, and an electromagnetic actuating unit for the spindle having a core, a magnet spool thereon, a return bar extending along the spool parallel to the core, and a bell crank armature mounted on said return bar and having an extended operating lever, said electromagnet and return bar being secured to the outside of the frame so that the core is substantially perpendicular to the 90 axis of the spindle, and said armature lever extending within the frame so as to bring its free end into operative relation with the spindle.

4. A selective switch for electrical systems 95 comprising bank contacts, a frame connected thereto, a spindle mounted in said frame, a movable contact or wiper carried on said spindle, and electromagnetic actuating means for the spindle separately assembled 100 and mounted as a unit upon the outside of the frame with actuating parts extending within the same so as to operatively engage the spindle.

5. A selective switch for electrical systems 105 comprising bank contacts, a U-shaped frame having its ends attached to the contact banks, a spindle extending across said frame with its ends journaled in the end members thereof so as to both reciprocate and turn therein, a vertical and a rotary ratchet adapted to set the spindle, a guide strip mounted in said frame parallel with the spindle so as to leave a working space between itself and the frame, a single dog 115 detent pivoted in the guide strip and adapted to engage the vertical and rotary ratchets, a series of spiral and a rotary magnet, both end-poled, carried on the frame with their axes perpendicular to the spindle, each having a core, a spool thereon, a return bar with a knife edge bearing on its end, a bell crank armature, and a spiral retractile spring therefor, the armature of the vertical magnet extending along the top of the return bar with its end projecting into the working space between the frame and guide strip, and having a pawl pivoted upon it with the end of the pawl extending 120 beyond the end of the return bar so as to 125 engage the vertical ratchet, and the 130

- engage the vertical ratchet and lift the spindle when the vertical magnet is energized; and the armature of said rotary magnet extending along the return bar thereof into 5 said working space, with a horizontal pawl pivoted thereon and extending through a guide slot in said guide strip, so as to engage the rotary ratchet wheel and turn the spindle when said rotary magnet is energized; together with means for disengaging 10 said detent from the ratchets, to permit the release and restoration of the spindle and movable contacts to their normal or zero position when the switch is not in use.
- 15 6. An electrical switch comprising bank contacts, supporting means therefor, a frame secured thereto bridging the contacts and spaced apart therefrom, a spindle journaled in the ends of said frame so as to have both reciprocating and rotary motion 20 therein, rotary and vertical ratchets on said spindle, and electromagnetic actuating units therefor, each comprising a core, a winding and a parallel return bar supported at one 25 end on the outside of the frame substantially perpendicularly to the spindle, an armature supported on the return bar and a lever extending therefrom to a point within the frame and there provided with a pawl 30 adapted to engage said rotary or said vertical ratchet as the case may be.
7. An electrical switch comprising bank contacts, supporting means therefor, a frame secured thereto bridging the contacts 35 and spaced apart therefrom, a spindle journaled in the ends of said frame so as to have both reciprocating and rotary motion therein, rotary and vertical ratchets on said spindle, and electromagnetic actuating units 40 therefor, each comprising a core, a winding and a parallel return bar supported at one end on the outside of the frame substantially perpendicularly to the spindle, an armature supported on the return bar and
- a lever extending therefrom to a point with- 45 in the frame and there provided with a pawl adapted to engage said rotary or said vertical ratchet as the case may be, together with means for holding the spindle in the position in which it may be set by the vertical or rotary magnets, and a release magnet consisting of a unit similar to the rotary and vertical units mounted on the outside of the frame and having an armature lever ex- 50 tending within the same to engage said holding means.
8. An electrical switch comprising an arc-shaped bank of contacts, a shallow U-shaped frame bridged across the ends of said bank, a "wiper carrying spindle journaled in bearings inside said frame, the axis of said journal bearings and of the spindle coinciding with the center or axis of the arc of the contact bank, and an operating electromagnet for said spindle having its core end 60 attached to the bridging frame in proximity to the spindle bearings and the axis of the core extending radially therefrom, a return bar extending from the frame parallel to the core and provided with a knife edge, an armature carried by the outer end on said knife edge and extending into proximity to the outer end of the magnet core, a lever 65 extending from said armature parallel to the core and return bar into proximity with the spindle, and an operating connection 70 between said lever end and the spindle, whereby armature movement at the outer end of the magnet will produce rotary movement of the spindle, and cause progressive 75 engagement between the wiper and bank contacts.
- In testimony whereof I affix my signature in presence of two witnesses.
